United States Patent Office.

CHARLES B. DAVIES, OF DAYTON, OHIO.

Letters Patent No. 84,266, dated November 24, 1868.

IMPROVED DEVICE FOR HANGING PICTURE AND OTHER FRAMES.

The Schedule referred to in these Letters Patent and making part of the same.

To whom it may concern:

Be it known that I, CHARLES B. DAVIES, of Dayton, in the county of Montgomery, and State of Ohio, have invented a new and useful Improvement in Method of Hanging Frames; and I do declare that the following is a true and accurate description thereof, reference being had to the accompanying drawings, and to the letters of reference marked thereon, and being a part of this specification.

The drawing shows a perspective of the rear side of the frame.

The object of this invention is to attach a cord and eyes, or rings, to the back of a picture or other frame, in such a manner that the frame may hang and be sustained at any inclination from the wall, without driving nails into or securing a bracket to the wall, under the frame, for that purpose.

To accomplish this purpose, I screw an eye, B, into the centre of the lower bar of the frame A, on its rear side. Similar eyes, C C', are screwed into the side bars, near their upper ends. At a proper height on the wall is secured a hook, in which is hung a ring, D. A cord E, one end of which is secured to the eye C, is

passed up and through the ring D, down and through the eye B, up through the ring D, down through the eye C', across the back of the frame, through the two outer holes in a slip, F, through the eye C, back to the slip, and its end secured to the same, through the central hole in the same.

When a frame is hung in this manner, its inclination with relation to the wall may be varied by simply moving it to the angle desired, where it will remain; the slip F being provided for lengthening or shortening the cord, and vertically raising or lowering the frame on the wall.

What I claim as my invention, and desire to secure by Letters Patent, is—

The method of hanging frames herein described, with the eyes B, C, and C', ring D, cord E, and slip F, when arranged with relation to the frame A, substantially as and for the purposes set forth.

CHARLES B. DAVIES.
